UNITED STATES PATENT OFFICE

HENRY P. TAYLOR, OF WINSTON-SALEM, NORTH CAROLINA

METHOD AND MEANS OF COMPRESSING TOBACCO

Application filed September 8, 1927. Serial No. 218,257.

This invention relates to the methods and means of compressing and packing tobacco by the use of sheets of comminuted fibrous material preferably soaked with paraffin or 5 similar substance prior to the compressing operation.

An object of my invention is to provide means for compressing and packing plug and twist tobacco in such a manner as to prevent 10 leakage in the hydraulic presses used for this purpose.

It is well known in the art that in the factories where plug and twist tobacco are made that the unpressed pieces of tobacco are 15 placed in a hydraulic press and there subjected to great pressure and it has been a common experience for the tobacco when undergoing the great pressure to which it is subjected will squirt by the movable heads in the 20 press. It is an object of my invention to prevent this escape of pressure and the consequent disfiguring of the finished product.

Some of the objects of my invention having 25 been stated, other objects will appear as the description proceeds when taken in connection with the accompanying drawings showing a preferred embodiment of my invention, in which—

Figure 1 is a side elevation partly in cross- 30 section of a tobacco press, showing my method and means;

Figure 2 is a side elevation partly in cross section, showing a box of tobacco having my 35 fibrous member therein;

Figure 3 is an enlarged edge view of one of the fibrous members shown in Figures 1 and 2.

Referring more particularly to the drawings the numeral 10 indicates the vertically 40 disposed supports of a tobacco press, the press being indicated by the numeral 11 which has forked projections 12, thereon which slide on both sides of the supports 10 and a lug 13 is secured to the supports 10 45 which is adapted to engage the projections 12 to support the press in its lowest position. Projecting into the upper end of the press member 11 is the plunger 14 which is fixedly secured in the press and extends into the 50 upper end of the press 11 and projecting into

the lower end of the press 11 is the movable plunger 15 which extends downwardly into a hydraulic chamber (not shown), and lying next to the plunger 15 is one or more steel plates such as is indicated by the numeral 16 55 and between the steel plate 16 and the plunger 14 the mass of tobacco is placed by means of a door in front of the press (not shown) or in some instances tobacco is placed into the press at the upper end. 60

Mechanism thus far described is conventional and it has been the experience of those skilled in the art heretofore that when the steel plate 16 is used next to the plungers 14 and 15 that when great pressure is applied 65 to the tobacco that the tobacco will squirt by the edges of the plate 16 after it has become slightly worn. I overcome this squirting by placing next to the tobacco a sheet of fibrous comminuted material indicated by the numeral 18, which is cut slightly larger than the press and this sheet of material 18 is thoroughly soaked in a solution of paraffin and after being removed from the paraffin 70 and allowed to dry. This sheet 18 is then placed in the press in the manner shown in Figure 1 and when a great pressure compressing the tobacco is applied the sheet 18 will be compressed also and the edges of the sheet 75 will assume a slightly enlarged position as shown in the drawings and the surface of the sheet 18 which is disposed next to the tobacco will assume a natural rough and ready finish and when the bulk of tobacco 17 is removed from the press the sheets 18 will be 80 very rigid and can be used as a head for packing the compressed tobacco into the caddies 85 and the sheet 18 can be used over and over again in the press 11. 90

In Figure 2 I have shown the sheet member 18 used in a caddy on box of tobacco 19 which shows the head members 18 secured in place by the conventional strips 20. By using these members 18 as the head members 95 for tobacco boxes to provide a head member which is impervious to moisture and which will at all times insure a natural rough and ready finish to the outer surfaces to the end plugs of tobacco.

In the drawings and specification I have 100

set forth a preferred embodiment of my invention, and although specific terms are employed, they are used in a generic and descriptive sense only, and not for purposes of limitation, the scope of the invention being set forth in the appended claim.

I claim:

- That method of pressing and packing manufactured tobacco which comprises im-
10 pregnating two sheets of fibrous comminuted material with a solidified oil, then placing one of said sheets in the bottom of a press, then placing a mass of tobacco in the press, then placing the other of said sheets in the
15 press on top of the mass of tobacco, then pressing the tobacco and pads together at one operation, then placing the pads and tobacco in a caddy having sidewalls only and confining the tobacco and pads in the caddy
20 to cause the pads to serve as head and bottom members of the caddy.

In testimony whereof I affix my signature.
HENRY P. TAYLOR.
